PISTON SKIRT ADJUSTER

Alfred Floyd Yoder, Akron, and David Milton Yoder, Barberton, Ohio

Application November 17, 1934, Serial No. 753,516

8 Claims. (Cl. 309—12)

This invention relates to pistons and more particularly to a means for expanding the skirt of a piston so as to take up any play between the piston and the cylinder wall of an internal combustion engine.

An object of this invention is to provide a means for enlarging the skirt of a piston which is readily adjustable so as to eliminate any piston slapping due to the wearing of the skirt and the cylinder wall.

Another object of this invention is to provide in combination with a piston having a split skirt means operable from below for adjusting the size of the skirt of the piston without removing any of the parts of the piston from the cylinder.

A further object of this invention is to provide in a device of this kind means whereby the adjusting means is automatically locked in adjusted position so that the enlarged or adjusted piston will not get out of adjustment in the operation of the engine.

A still further object of this invention is to provide a means for adjusting the diameter of the skirt of a piston which is so constructed that it can be readily mounted in any of the present types of pistons provided with skirts and when once mounted, the adjusting means may be readily actuated to change the size of the diameter of the skirt without removing the piston or its connections from the engine.

The above and various other objects and advantages of this invention will in part be described and in part be understood from the following detailed description of the present preferred embodiment, the same being illustrated in the accompanying drawing wherein:

Figure 1 is a detail side elevation of a conventional piston having a split skirt in which a device constructed according to the preferred embodiment of this invention is mounted.

Figure 2 is a transverse section taken on the line 2—2 of Figure 1.

Figure 3 is a vertical section taken on the line 3—3 of Figure 2.

Figure 4 is an enlarged detail side elevation of the piston adjusting means removed from the piston.

Figure 5 is a modified form of adjusting means for the skirt of the piston.

Referring to the drawing wherein like characters of reference designate corresponding parts throughout the several views thereof, the letter P designates generally a piston provided with a skirt portion S which is split, as at 13. In internal combustion engines, after the engine has

been in use for a period of time, the pistons in the cylinders and the cylinder walls wear to such an extent that there is a considerable slapping or loose play between the skirt of the piston and the cylinder wall, which play permits the relatively free passage of oil or the like from below the piston onto the upper portion thereof and in this manner, a substantial pumping of oil is effected which oil is then discharged out of the cylinder through the exhaust ports of the engine.

In order to prevent the pumping of oil and the slapping of the piston, the usual method is to re bore and insert pistons having a diameter to slidably and snugly engage the rebored cylinders or to insert larger pistons in the unrebored cylinders. This latter method, however, has the disadvantage of inserting a round piston in a cylinder, the walls of which are not round but slightly oval on opposite sides.

Where either of the above mentioned methods is used to prevent pumping of oil and to increase the compression, it is necessary to take the motor apart, which procedure involves the removal of the head of the motor, removal of the oil pan and disconnection of the pistons from the crank shaft.

In order, therefore, to provide a means whereby the original piston having a split skirt may be enlarged without requiring the taking apart in such a complete manner of the motor, we have provided a skirt adjusting means comprising a pair of pins or abutments 10 which are disposed one on each side of the split portion 13 of the skirt S and at a point intermediate the ends of the skirt S. The pins 10 in the present instance are headed pins which are secured in the wall of the skirt S in any suitable manner so that the outer ends of the pins 10 will not project beyond the periphery of the skirt S and thereby injure the wall of the cylinder of the engine. The pins 10 in the present instance are inserted in suitable openings and fixed in the openings but it will, of course, be understood that the pins or abutments 10 may also be made integral with the material of the skirt S as where the pins 10 are cast or formed at the same time that the piston proper is cast.

A skirt expanding means generally designated as 11 engages the pins or abutments 10 and comprises opposed pairs of angularly related arms 12 and 14 connected together at their convergent ends as by a coil 15 which loosely engages about a pin 10 inwardly of the head thereof. The lower or divergent end of the opposed arms 12 are connected together by means of a coil or loop 16

which loosely engages about an adjusting bolt 17 having a head 18 provided with a kerf 19. The bolt 17 has a nut 20 threaded thereonto and this nut 20 has a pair of parallel arms 21 disposed in opposed relation and provided with openings 22 in which the end portions 23 of the opposed arms 14 are loosely received. The opposed ends of the arms or extensions 23, when the nut 20 is drawn toward the eye or loop 16, 10 are adapted to contact with the peripheral portions of the threads on the bolt 17 and thereby act as a locking means to lock the nut 20 and prevent the bolt 17 from turning when the pistons are moving up and down within the cylinder. 15 The opposed arms 12 and 14 form a parallelogram and the bolt 17 transects the parallelogram through opposite corners.

In Figure 5 there is disclosed a modified form of adjusting means for the skirt S of the piston 20 wherein the arms 12' and 14' are formed as a toggle and engage at their convergent ends about the pin 10'. The toggle member 12' is pivotally secured, as at 24, to an angle member 25 and the upper or divergent end of the toggle member 25 14' is pivotally secured, as at 26, to an angle nut member 27 threaded onto an adjusting bolt 17'. The bolt 17' passes through the angle member 25 and the relatively rigid arms 12' and 14' form a parallelogram in the same manner as the 30 disclosure shown in Figure 4.

In the use and operation of the skirt adjusting means hereinbefore described where the device is mounted on a piston of an engine which has been in operation for a period of time, the piston 35 is initially withdrawn from the cylinder of the engine and the walls of the skirt S bored to receive the pins 10 which are inserted with the heads on the inner side thereof. The outer ends of the pins 10 may be upset or secured in any 40 other suitable manner in the walls of the skirt S on opposite sides of the slot 13. The pins 10 are passed through the eyes 15 of the adjusting member before being fastened in the wall of the skirt and the adjusting bolt 17 will be loosened so that no pressure will be applied initially 45 to the nut 20. It will, of course, be understood that the arms 12 and 14 are preferably curved longitudinally, as shown in Figure 2, so that they will lie flat against the inner circle of the skirt S. After the adjusting member 11 has been mounted within the skirt S, the bolt 17 is turned so as to draw the arms 12 and 14 toward each other under the action of the bolt 17 which will tend 50 to force the divergent ends or eyes 15 apart and this action will cause expansion of the slot 13 and the walls of the skirt S. After the adjusting member 11 has been applied to the piston F, the skirt S may be readily adjusted by merely removing the oil pan from the bottom of the motor 60 and then inserting a screw driver into the cylinder for engagement in the kerf 19 of the screw head 18.

In the disclosure shown in Figure 4, the adjusting member 11 is constructed from a piece of 65 wire which is formed with the opposed eyes 15 and the eye 16. It will also be apparent that the tightening of the nut 20 will tend to put the arms 12 and 14 under considerable tension so that the skirt S will be expanded and held in its 70 expanded position and in addition thereto, the skirt S will continue to be expanded as the periphery of the skirt wears down.

It will be obvious from the foregoing that an 75 exceedingly simple piston adjusting means has been disclosed whereby the diameter of the skirt

of the piston may be adjusted without removing the piston from the cylinder once the device has been applied and that the diameter of the skirt of the piston will automatically change so long as the device is under tension, thereby providing 5 an automatically operated adjusting means which will act to maintain the skirt of the piston of a diameter sufficient to prevent slapping of the piston within the cylinder.

What is claimed is:—

1. An adjusting means for the skirt of a split piston, comprising a pair of pins adapted to be secured to the inside of the skirt of the piston one on each side of the split portion thereof, pairs of angularly related members secured one pair to 15 each pin, each member of each pair being movable relative to each of the other members, threaded means engaging said angularly related members to adjust the angular relation of said members one relative to another whereby to enlarge the split portion of the skirt of the piston and locking means carried by one member of each pair of angularly related members to hold the threaded means against turning.

2. An adjusting means for the skirt of a split 25 piston, comprising pairs of angularly related arms adapted to be disposed one pair on each side of the split portion of the piston, means for securing the convergent ends of each pair of arms to the wall of the piston, and means extending 30 between the divergent ends of the arms to draw said divergent ends toward each other and to thereby force the convergent ends of the arms apart and thereby expand the skirt of the piston.

3. An adjusting means for the skirt of a piston, 35 comprising a pair of pins adapted to be mounted in the skirt of a piston and to project inwardly thereof one on each side of the split portion of the piston, opposed pairs of angularly related arms, an eye formed integrally with the convergent ends of each pair of arms, said eye of 40 each pair of arms loosely engaging about a pin, a bolt extending between the divergent ends of the arms, two of said arms having an integral eye at the adjacent divergent ends thereof, a 45 nut threaded onto said bolt and provided with alined openings disposed at right angles to the bolt, the other two arms at the divergent ends thereof having an extension engaging within said opening, said extension upon tightening of 50 the nut frictionally engaging the periphery of the bolt whereby to lock the bolt against turning, tightening of the nut on the bolt drawing the divergent ends of the arms together to thereby expand the split portion of the skirt.

4. An adjusting means for the skirt of a split piston, comprising a pair of pins adapted to be mounted in the skirt of the piston on the inside thereof and to project inwardly of the skirt one on each side of the split portion, a pair of 60 toggle members adapted to be disposed on each side of the split portion of the piston, said toggle members swingably engaging at their convergent ends about a pin, an adjusting bolt extending between the divergent ends of the toggle members, 65 a plate secured to the ends of one of each pair of toggle members and loosely engaging about the bolt, and a second plate secured to the other of each pair of toggle members and threadably engaging the bolt.

5. An adjusting means for the skirt of a split piston comprising a pair of pins adapted to be secured to the inside of the skirt, one on each side of the split portion thereof, pairs of angularly related members secured one pair to each 75

pin, each member of each pair being movable relative to each of the other members, a right angularly related eye carried by two of said members, a bolt extending through said eye and a nut for receiving the bolt carried by the other two of said members.

5. An adjusting means for the skirt of a split piston comprising a pair of pins adapted to be secured to the inside of the skirt one on each side of the split portion thereof, pairs of angularly related members secured one pair to each pin, each member of each pair being movable relative to each of the other members, a right angularly related eye carried by two of said members, a bolt extending through said eye, a nut for receiving the bolt, and means integral with the ends of said other two of said members to mount the nut in axial alinement with said eye.

6. An adjusting means for the skirt of a split piston comprising a pair of pins adapted to be secured to the inside of the skirt one on each side of the split portion thereof, pairs of angularly related members secured one pair to each pin, each member of each pair being movable relative to each of the other members, a right angularly related eye carried by two of said members, a bolt extending through said eye, a nut for receiving the bolt, and means integral with the ends of said other two of said members to mount the nut in axial alinement with said eye.

7. An adjusting means for the skirt of a split piston comprising a pair of pins adapted to be secured to the inside of the skirt one on each side of the split portion thereof, pairs of angularly related members secured one pair to each pin, each member of each pair being movable relative to each of the other members, a right angularly related eye carried by two of said members, a bolt extending through said eye, a nut for re-

ceiving the bolt and confronting nut engaging pins integral with the ends of said other two members, said nut having aligned openings to loosely receive said pins and the inner ends of said pins frictionally contacting with the periphery of said bolt within the nut to hold the bolt against turning.

8. An adjusting means for the skirt of a split piston comprising a pair of pins adapted to be secured to the inside of the skirt one on each side of the split portion thereof, pairs of angularly related members secured one pair to each pin, each member of each pair being movable relative to each of the other members, a right angularly related eye carried by two of said members, a U-shaped nut having a threaded opening in the bight thereof, said nut having a pair of aligned openings in the parallel legs thereof, a pair of confronting nut engaging pins carried by the other two of said members and engageable in the openings of the nut and a bolt extending through said eye and threadably engaging said nut, said pins being movable toward the bolt upon expansion of the skirt whereby to frictionally hold the bolt against turning.
